UNITED STATES PATENT OFFICE.

ANTON JOCH, OF CLEVELAND, OHIO.

VENTILATOR.

1,109,927.

Specification of Letters Patent.

Patented Sept. 8, 1914.

Application filed July 5, 1913. Serial No. 777,450.

To all whom it may concern:

Be it known that I, ANTON JOCH, a citizen of the United States, residing at Cleveland, in the county of Cuyahoga and State of Ohio, have invented a certain new and useful Improvement in Ventilators, of which the following is a full, clear, and exact description, reference being had to the accompanying drawings.

10 This invention relates to improvements in ventilators of the cowl type; and has for its object the provision of such a ventilator which is extremely efficient; convenient of operation; and comparatively simple of construction.

15 The efficiency of my improved ventilator is considerably greater than that of prevailing ventilators of the same general type, and this is due to the fact that the closure for the top of my ventilator is capable of being raised, providing thereby an exhaust opening of considerable area in addition to that provided by the usual louver controlled exhaust opening. An important feature of my 20 invention is the simple, yet very efficient mechanism whereby the closure for the top of the ventilator is raised and retained in such position; and the mechanism whereby the louvers are operated and held open.

25 30 These features are clearly illustrated in the accompanying drawings forming a part hereof, which show a ventilator constructed in accordance with my invention and whereby I obtain the objects above set forth.

35 In the drawings, Figure 1 is a central vertical section through the ventilator; Fig. 2 is a horizontal section on the line 2—2 of Fig. 1 and looking down; Fig. 3 is a view, similar to Fig. 1, with the cover of the cowl 40 raised and the louvers in open position; and Figs. 4, 5 and 6 are sectional details of parts of the louvers.

45 The ventilator comprises, generally, an upper and a lower section, the former being rotatable and referred to hereinafter as the cowl, and the latter being stationary, and referred to as the base; and for convenience, that portion of the cowl which is presented to the wind will be considered the "front," 50 and its opposite side, or that containing the louver controlled opening, the "rear."

55 Referring to the drawings by the use of reference characters, 1 represents the cowl and 2 the base whereby the cowl is rotatably supported in a manner which will be explained hereinafter. The cowl comprises a

substantially cylindrical shell which is open at the bottom and has its lower edge wired as shown at 3 in the usual manner. The upper end of the shell whereof the cowl is formed is inclined upwardly from front to rear and is provided with a cover 4. Directly at its front a portion of the cover is flared outwardly into a substantially horizontal flange 5 which is of considerable lateral extent. To each end of this flange is secured in any convenient manner, as by riveting, a plate 6, shown in dotted line in Fig. 2. These plates terminate at their outer ends in cylindrical bosses which form 60 gudgeons 7 for the cover 4, and the gudgeons are journaled in one of the forwardly extending branches of the angular brackets H, the inwardly extending vertical branches whereof are riveted to the front of the cowl. 65 The edge of the cover 4, except that portion which forms the flange 5 is turned downwardly to form a flange 9, and this flange is stiffened by a band 10 which is secured to it by rivets 11. It will be seen, therefore, that 70 I provide a very strong cover for my ventilator which is hinged in a very substantial manner to the front of the cowl. A substantially square hole is made in the rear of the cowl and is surrounded by a box-shaped casing 12 which comprises horizontal top and 75 bottom walls 13 and side walls 14, the former being secured to the cowl through flanges 15 which are made integral with the cowl and extend therefrom into the interior of the 80 casing 12, and the rear of the latter walls 14 having flanges 16 whereby they are secured to the shell of the cowl adjacent the sides of the aforesaid opening. The opening through the casing 12 is adapted to be closed 85 by a series of louvers 17 which are pivoted a slight distance above their vertical centers to the side walls 14 of the casing 12. The novel method of pivoting the louvers to said side walls involves the making of three slits 90 near each end of each louver bisecting the axes whereon the louvers are pivoted, and the strips of material between the slits (which is indicated at 18 and shown particularly in Figs. 4 and 5) are curved in opposite directions. Adapted to be inserted from the end of each louver into the substantially circular socket provided by the alternately disposed curved strips 18 is a 95 pintle 19, and that portion of the pintle 18 which is adjacent the intermediate strip 18 has a pair of oppositely projecting fins 20. 100 105 110 115

In assembling the parts, the alternate strips 18 are separated a sufficient distance to permit the fins 20 to be inserted into position whereafter the strips are pressed firmly about the pintle, thus securing the pintle in place by the engagement of one end of the fins 20 with the adjacent edge of the first strip 18, and preventing the displacement or withdrawal of the pintle. Riveted or otherwise secured to each louver near its lower edge and at substantially its longitudinal center is a loop 21 which is adapted to embrace one of the pins 22 supported within the side flanges of a channel which forms a link 23 whereby all of the louvers are connected together and are moved in unison when one of the louvers is swung upon its pivot. The louvers are provided with the usual overhanging flanges 24 and 25.

The cowl 1 is carried by a central tubular post 26 to which it is secured by angle-iron braces 27 which have a portion of the outer ends of their horizontal flanges turned downwardly and fastened by bolts 28, to the cylindrical shell of the cowl, said outer ends being spaced at points thereabout approximately 120° apart. The braces 27 converge toward the center of the cowl where their inner ends are secured to ears 29 which project radially from the upper end of a cast-metal cylindrical block 30. This block is preferably shrunk upon the upper end of the post 26 and its lower end is tapered downwardly toward the post to form a cone 31 of a ball bearing.

Centrally located within the cylindrical shell or base 2 is a tube 32, supported from said shell by braces 33 which are secured by screws 34 to a sleeve 35 which may be shrunk upon the tube 32 near its lower end, and which project upwardly and outwardly therefrom to where their outer ends are riveted between the shell and the outer down-turned end of tie strips 36, the inner ends of the strips 36 being secured to the legs of a spider 37 which surrounds the tube 32 in any desired manner, as by bolts 38. Three of such braces and strips are employed and they are spaced at equal distances about the base, thereby providing a very substantial support for the tube 32. The upper end of the tube 32 is threaded for the reception of a nut 39, and the top face of the nut contains a recess which has an inclined bottom wall 40 to form a raceway for the balls 41 of a ball-bearing whereof the aforesaid cone 31 forms the other member. The post 26 projects downwardly through the tube 32 and is centralized at its lower end by the inwardly extending flange 42 of a nut 43 which is threaded upon the lower end of the tube 32. A collar 44 which is secured to the lower end of the post 26 by a set screw 45, holds the post against vertical displacement.

The mechanism for raising the cover 4 of the cowl and for retaining it in raised position, will now be described.

Bolted to the rearwardly extending braces 27 are a pair of brackets 46 which extend upwardly and toward each other. Their adjacent ends are vertical and parallel, being spaced apart a slight distance for the accommodation of the lever 47 which is pivoted therebetween upon a bolt 48, carried by said brackets. The rear end of the lever 47 is pivotally connected to a link 49, which, in turn, is pivoted at its opposite end to an ear 50 which depends from the cover 4 at about its center. The shorter and forward end of the lever 47 repose, normally, directly above the upper end of the post 26 and has secured to it a cable 51 which passes downwardly through said post to the inside of the building whereon the ventilator is located. Projecting into the path of movement of the forward end of the lever 47 is the turned over end of a spring 52, its opposite end being secured to the rearwardly extending brace 27 by the same bolt whereby the brace is secured to the ear 29 of the block 30. While this is my preferred form of fastening the spring to a stationary part of the cowl, it is obvious that other methods might be employed for this purpose, such, for instance, as riveting the spring to the brace, or securing it thereto by additional bolts. Moreover, the manner described makes an economical construction since the edge of the spring will engage the vertical flange of the angle-iron whereof the brace 27 is formed, thus holding the spring in proper position even though but one bolt is used for its attachment.

When it is desired to raise the top of the ventilator, the cable 51 is drawn downwardly until the forward end of the lever 47 passes the free end of the spring 52, the spring yielding to permit of such an operation. The cable 51 is then gently relaxed, allowing the end of the lever to bear against the spring, as shown in Fig. 2, the tension of the spring being sufficient, of course, to retain the parts in this position under ordinary conditions. To lower the top, it is only necessary to pull downwardly on the cable 51 and quickly release it, when the inertia of the cover 4 will be transferred through the link 49 and lever 47 to the spring and force it beyond the front end of the lever 47, permitting said lever, with the other parts, to return to normal position. Furthermore, the tension of the spring 52 is such as will permit it to yield and allow the cover to close in case the wind rises to a high velocity when it would be undesirable to have the cover of the ventilator raised.

To open the louvers 17 of the ventilator, I employ mechanism which comprises a curved arm 53 which is pivoted at 54 to a

bracket 55, carried by the brace 27 whereon the spring 52 is mounted and to the rear of said spring. Projecting rearwardly through a slot 56 which is formed within the block 50 and the post 26, the arm 53 terminates within a short distance of one of the louvers 17. Carried by this louver is a curved plate 57 having its outer end notched at 58 to form a guide for the free end of the arm 53, and the lower portion of the adjacent end of the arm is cut away to form a shoulder 59. Secured to the arm 53 within the post 26 is a cable 60 which extends downwardly through the post in juxtaposition to the cable 51. When this cable is pulled, it swings the arm 53 downwardly and by the engagement of the lower edge of its forward portion with the bottom of the notch 58, the louver which carries the bracket 57 is swung upon its pivot to substantially horizontal position, as shown in Fig. 2, and by reason of the connection of all of the louvers through the link 23, said louvers are swung to a similar position simultaneously. When in the position shown in Fig. 2, the shoulder 59 abuts the bottom of the notch 58 of the plate 57, and since such point of engagement is below the common plane of the pivot points of the arm 53 and the louvers 17, the said parts will remain in such position, the weight of the lower ends of the louvers and the link 23 accentuating such an action. A spring 61 is carried by one of the forwardly extending braces 27 and preferably secured thereto by the same bolt which connects one of the brackets 46 to said brace, and is curved downwardly and forwardly toward the center of the ventilator where it ends in substantially the vertical plane of the arm 53. Directly beneath the arm, the spring is provided with an adjustment screw 62. The closing of the louvers is accomplished by a quick jerk on the cable 60 and this quick movement is imparted to the louvers through the engagement of the reduced end of the arm 53 with the bracket 59. The return movement of the louvers is comparatively slow (because of the proportion of their parts) as compared to the quick upward movement of the arm 53 which is caused by the recoil of the spring 61, said spring being placed under tension when the bottom edge of the arm 53 has depressed the adjustment screw 62. This action allows the disengagement of the shoulder 59 from the bottom of the notch 58 and the parts are free to return to normal position, the arm 53 being raised by the weight of the outer edges of the louver 17 and the link 23.

Having thus described my invention, what I claim is:—

1. In a ventilator, the combination, with a tubular base, of a cowl rotatably supported thereby and having an opening in its top

and an opening in one side, and a cover for said cowl which is hinged to that side of the cowl opposite the aforesaid opening.

2. In a ventilator, the combination with a tubular base, of a cowl rotatably supported thereby and having an opening in its top and an opening in one side, and a cover for said cowl which is hinged to that side of the cowl opposite the aforesaid opening, and mechanism for raising said cover. 70

3. In a ventilator, the combination, with a tubular base, of a cowl rotatably supported thereby and having an opening in its top and an opening in one side, a cover for said cowl which is hinged to that side of the cowl opposite the aforesaid opening, mechanism for raising said cover, and means for retaining the mechanism in cover raising position. 75

4. A ventilator comprising, in combination, a cowl having an opening in one of its sides, a louver pivotally supported within said opening, a bracket carried by the louver, and an arm pivoted within the cowl the free end of which overhangs the end of the aforesaid bracket, the end of said arm being arranged to abut the end of the bracket when the louver is in open position. 85

5. A ventilator comprising, in combination, a cowl having a substantially rectangular opening in one side thereof which is surrounded by a frame, a series of louvers pivoted within said frame and having their corresponding edges linked together, a bracket carried by one of the louvers said bracket 95 extending toward the interior of the cowl and having a portion of its end in a substantially parallel plane with the louver there being a notch within such end, and an arm pivoted within the cowl and extending 100 toward said bracket and through the notch therein, the free end of the arm having a shoulder which is arranged to abut the bottom of said notch, when the louver is in open position. 105

6. A ventilator comprising, in combination, a cowl having a substantially rectangular opening in one side which is surrounded by a frame, a series of louvers pivoted within said frame and having their corresponding edges linked together, a bracket carried by one of the louvers, said bracket extending toward the interior of the cowl and having a portion of its end in a substantially parallel plane with the louver, and an arm pivoted 115 within the cowl the free end of which overhangs the end of the aforesaid bracket, the end of said arm being arranged to abut the end of the bracket when the louvers are in open position. 120

7. A ventilator comprising, in combination, a cowl having an opening in one side thereof, a louver pivotally supported within said opening, a bracket carried by the louver and extending toward the interior of the 130

cowl, an arm pivoted within the cowl the free end of which overhangs the end of the aforesaid bracket, and a yielding abutment for engagement by the arm when the arm is 5 swung downwardly below a predetermined position, the abutment tending to return the arm to such predetermined position.

8. A ventilator comprising, in combination, a cowl having an opening in one side thereof, a louver pivotally supported within said opening, a bracket carried by the louver and extending toward the interior of the cowl, an arm pivoted within the cowl the free end of which overhangs the end of the aforesaid bracket, a yielding abutment for engagement by the arm when the arm is 10 swung downwardly below a predetermined position, the abutment tending to return the arm to such predetermined position, and 15 means for adjusting the elevation of the abutment.

9. A ventilator comprising, in combination, a cowl having an opening in one side thereof, a louver pivotally supported within

said opening, a bracket carried by the louver 25 and extending toward the interior of the cowl, an arm pivoted within the cowl the free end of which overhangs the end of the aforesaid bracket, a spring secured within the cowl and projecting beneath the aforesaid arm, and an adjustment screw carried by the spring for engagement by the arm.

10. A ventilator comprising, in combination, a cowl having an opening in one side thereof, a louver pivotally supported within 30 said opening, a bracket carried by one of the louvers and extending toward the interior of the cowl, an arm pivoted within the cowl the free end of which overhangs the end of the aforesaid bracket, and a spring secured 35 within the cowl and projecting beneath the aforesaid arm for engagement thereby.

In testimony whereof, I hereunto affix my signature in the presence of two witnesses.

ANTON JOCH.
